UNITED STATES PATENT OFFICE.

WILLIAM JOHN WALKER, OF WARRINGTON, ENGLAND.

APPARATUS FOR TREATING LEATHER OR OTHER GOODS.

1,365,573.

Specification of Letters Patent.

Patented Jan. 11, 1921.

Application filed December 15, 1919. Serial No. 345,060.

To all whom it may concern:

Be it known that I, WILLIAM JOHN WALKER, a subject of the King of Great Britain, and a resident of Warrington, England, have invented certain new and useful Improvements in Apparatus for Treating Leather or other Goods, of which the following is a specification.

This invention relates to apparatus for use in the manufacture or treatment of leather or other goods and refers more particularly to such apparatus wherein the goods are suspended and moved about in a vat containing the treating liquor, mechanical means being provided to agitate the liquor. The object of the present invention is to provide improved and simplified means for agitating the liquor.

According to this invention, the device comprises an agitator for the liquor consisting of a valve frame fitted with a series of flap or non-return valves, the frame being caused to reciprocate vertically in the liquor and also to agitate it. A series of such frames may be provided, and arranged in two sets, one set being arranged to rise while the other set falls, this action being obtained by suspending the frames by means of ropes, belts, or the like flexible elements passing over pulleys and connected to a sliding board, rod, or rods which are reciprocated, say from a shaft. The apparatus is particularly applicable to the manufacture of leather and a type of valve agitator as described may be used in combination with a frame from which the hides are suspended, the frame and the hides rising and falling in the vat the base of which frame is arranged as a valve agitator, or the hides may be suspended in any suitable manner within the vat and fixed, the agitator then being a separate element and vertically reciprocated to agitate the vat liquor. The hinged valves may be resiliently controlled so as to insure a more rapid action in closing.

The invention is illustrated, as applied to the manufacture of leather, in the accompanying drawings, in which Figure 1 is a plan view of an agitator or valve frame constructed principally of timber. Fig. 2 is a section on the line A—A of Fig. 1. Fig. 3 is a plan view analogous to Fig. 1, of a concrete type of valve frame, Fig. 4 being a section on the line B—B, Fig. 3, and Fig. 5, a section on the line C—C Fig. 3. Fig. 6

is an elevation, and Fig. 7, a plan view, showing a frame for supporting the hides combined with an agitator of the type shown in Figs. 1 or 3. Fig. 8 is an elevation showing a series of agitators with their driving gear, and Fig. 9 is a plan of Fig. 8.

In carrying out the invention, as applied to the manufacture of leather with which the invention is principally concerned, the liquor in the vats is agitated by means of a valve frame 1 which in Figs. 1 and 2 is constructed of wood. This valve frame is fitted with a series of cavities 2 controlled by means of valves 3 which may take the form of boards 4 hinged at 5, or direct lifting valves 6 which are free to rise on the studs 7 carried from transverse bars 8, the valves 4 and 6 as the frame 1 is caused to fall opening upward on the downward movement of the frame and permitting the liquor to pass therethrough. On the subsequent rising movement of the frame the valves close and a partial vacuum being set up beneath the valve frame the liquor as it is lifted is caused to flow around the exterior of the frame downward into the vat, the valve frames occupying a considerable area of the vat. In order to insure that the valve frame shall fall in the liquor it may be weighted as required. The valve frames may have slightly upstanding walls so as to form a cavity above, if so desired, and are fitted with any suitable means such as the ring bolt 9 for raising and lowering them in the liquor. In the arrangement shown in Figs. 3 to 5 the frame 1 is made of concrete to assist the sinking action of the valve frame, the valves 4 in this case being hinged back to back and the hinge taking the form of rubber plates 10 carried beneath the transverse bars 11. Apertures 2 are also in this case cast in the concrete frame 1^a, and the ring bolt 9 again provided for manipulating the valve frame. The concrete frames may be reinforced by H-girders 12, as shown in Fig. 4, to strengthen them and increase their weight so that they may sink the more effectually in the vat liquor.

Such a valve frame may be used to cause the agitation of the liquor in any existing type of vat, and the hides may then be suspended in the vats in any suitable and known manner. A valve frame as described, however, may be used in combination with a supporting frame for the hides, the hides in that case, as well as the valve agitator,

rising and falling in the liquor. This arrangement is illustrated in Figs. 6 and 7, where the hides 13 are supported from rods 14 carried on an upper framework 15 distanced by corner posts 16 from a base 1, which may be a valve agitator of the form shown in Figs. 1 or 3. The whole combined hide supporting framework and valve agitator are moved up and down in the vat liquor from the ring 9^a and chains 17 connected to eye bolts 18 at the corners of the upper frame 15. The rods 14 from which the hides are suspended may be anchored down at their ends by retaining bars 19 to prevent them lifting when being submerged in the vat liquor, or the hides and skins may be supported in any other suitable manner.

Where valve agitators only are used for circulating the vat liquor, the hides being fixed, or where the valve agitators are used in combination with hide supporting frames, the agitators are preferably arranged in series alternately rising and falling. The means for effecting such a movement is illustrated in Figs. 8 and 9, where the valve agitators are arranged in two series 1^a, 1^b, within the vats 20, the series of vat frames 1^a rising, while the series 1^b fall, and vice-versa. This is effected by suspending the frames by means of ropes or the like flexible elements 21^a, 21^b, passing over pulleys 21^c and connected at 22 to a sliding rod or rods 23 which is or are reciprocated from a shaft 24 carrying an eccentric 25 or the like coupled by a connecting rod 26 to the sliding rod or rods 23, so that rotary movement of the shaft 24 sets up a reciprocatory movement of the sliding rods and alternating rising and falling movement of the frames. By arranging the frames in the manner shown the weight of the descending frames assists the action of the rising frames, and the total power required to drive the system is thus reduced to a minimum.

The apparatus may be used for the various treatment of hides and skins such as soaking, liming, de-liming and tanning and when applied to processes other than the manufacture of leather as for instance the

treatment or dyeing of textiles, the material would be carried from the frames in the same way as that described above.

I claim.

1. An agitating mechanism for soaking or similarly treating hides, skins, leather or other goods, comprising, a vat for the liquor, a frame reciprocated vertically in the liquor and extending over a considerable area of the vat, said frame being adapted to bodily rise and fall, a series of non-return valves in said frame, said valves being adapted to open on the downward movement of the frame and close on the return movement, and means for vertically reciprocating the frame.

2. An agitating mechanism for soaking or similarly treating hides, skins, leather, or other goods, comprising, vats for the liquor, a series of frames reciprocated vertically in the liquor, each frame extending over a considerable area of its vat, said frames each having a series of large apertures, a series of non-return valves controlling said apertures, said valves being adapted to open on the downward movement of the frames and close on the return movement, the series of frames being supported by flexible elements passing over pulleys and being arranged in two sets, the one set descending as the other set rises so that the weight of the descending frames assists the action of the rising frames, and means for vertically reciprocating the frames.

3. Mechanism of the class described comprising, in combination, vats, a series of valved frames arranged in sets within the vats for agitating the contents thereof, and means for vertically reciprocating said frames including connections between the frames and said reciprocating means to cause the frames of each set to alternately rise and fall.

In testimony whereof I affix my signature in presence of two witnesses.

WILLIAM JOHN WALKER.
